(57) **CLAIM**

The ornamental design for a stick treat dispenser for pets, as shown and described.

DESCRIPTION

FIG. 1 is a perspective view of a stick treat dispenser for pets showing our new design;

FIG. 2 is a top plan view;

FIG. 3 is a bottom plan view;

FIG. 4 is a right side elevational view, the left side being the mirror image thereof;

FIG. 5 is a front elevational view;

FIG. 6 is a rear elevation view;

FIG. 7 is a perspective view of an alternative embodiment of a stick treat dispenser for pets;

FIG. 8 is a top plan view;

FIG. 9 is a bottom plan view;

FIG. 10 is a right side elevational view, the left side being the mirror image thereof;

FIG. 11 front elevational view; and,

FIG. 12 rear elevation view.

The broken lines in the drawings represent portions of the stick treat dispenser and stick treats for pets which form no part of the claimed design.

1 Claim, 10 Drawing Sheets
